INHALER

Joseph B. Biederman, Cincinnati, Ohio

Application October 6, 1943, Serial No. 505,090

1 Claim. (Cl. 128—200)

1

This invention relates to improvements in an inhaler, particularly a nasal inhaler.

Nasal inhalers are well known and in the past have utilized containers which are relatively expensive, thereby increasing the cost to the user of an inhaler without increasing the efficiency of the device. Furthermore, inhalers as heretofore used had no means of regulation, that is, no way to regulate the amount of the drug, medicine or fumes which the user could inhale at any given time wherefore, the user always received a full dose whether it was necessary or not. By this invention there is provided an inhaler utilizing an inexpensive container thereby enabling the production of an inhaler which is economical to purchase and use, and at the same time provide an inhaler from which a regulated amount of medicine in the form of vapor may be extracted.

It is, therefore, an object of this invention to provide an inhaler container of simple inexpensive construction yet efficient in operation.

Another object of this invention is the provision of an inhaler container provided with means whereby the vapor extracted therefrom can be regulated.

Another object of this invention is the provision of an inhaler container that can be shut off to prevent the extraction of medicated vapors or can be adjusted to permit varying amounts of the vapors up to a maximum.

Other objects and advantages of the present invention should be readily apparent by reference to the following specification considered in conjunction with the accompanying drawings forming a part thereof and it is to be understood that any modifications may be made in the exact structural details there shown and described, within the scope of the appended claim, without departing from or exceeding the spirit of the invention.

In the drawings:

Fig. 1 is a side elevational view of the container of this invention.

Fig. 2 is a vertical sectional view through the device of Fig. 1.

Fig. 3 is a top plan view of the device as seen in Figs. 1 and 2.

Fig. 4 is a bottom plan view of the device as seen in Figs. 1 and 2.

Fig. 5 is a horizontal sectional view through the lower end of the container, taken on line 5—5 on Fig. 1.

Fig. 6 is a view similar to Fig. 5 showing the parts in an extreme adjustment from that of Fig. 5.

Fig. 7 is a perspective view of the body portion and bottom member of the container and forming details of the invention.

Fig. 8 is a vertical sectional view similar to

2

Fig. 2, showing a modification in the construction of the container.

Fig. 9 is a horizontal sectional view taken on line 9—9 on Fig. 8 and showing one member of a closure for the container.

Fig. 10 is a horizontal sectional view taken in a plane below that of Fig. 9 on line 10—10 on Fig. 8 and showing the second member of the container closure.

Throughout the several views of the drawings similar reference characters are employed to denote the same or similar parts.

As was noted above, this invention pertains to an inhaler and particularly to the casing or container thereof. This inhaler is of the type commonly used in the treatment of head colds for permitting the administering of vapors to the nasal and head passages to ease the discomfort resulting from the cold.

Specifically the inhaler casing comprises a body member 10 having at one end a bottom member 11 and at its other end a top member 12. The body member 10 is formed of a sheet of thin metal rolled to have the opposite ends of the sheet in abutment and secured to one another by solder as at 13. The lower end of the body member 10 is provided with a series of holes or apertures 14 which, sequentially, are spaced at equal distances from each other circumferentially of the lower end of the said body member and preferably diametrically arranged.

The bottom member 11 is substantially cup shaped, including the bottom 15 with a flange 16 rising therefrom within which the said lower end of the body 10 is received. The bottom member flange 16 is provided with a series of holes or apertures 17, each of which is equally spaced from adjacent apertures. Apertures 17 in the bottom member 11, similar to the apertures 14 in the body member 10, are diametrically arranged.

The bottom member 11 is loose on the body 10 to the extent necessary so that it may be rotated or adjusted thereon but not loose enough that it falls by its own weight from the said body member. By this construction the bottom member 11 may be arranged with respect to the body 10 to have its apertures 17 located between the apertures 14 of the body member 10 and thereby prevent any air passage through the said apertures. By the arrangement just described the bottom member 11 may be adjusted so that each of the apertures 17 is in registry with its corresponding aperture 14 whereupon a maximum amount of air is permitted to enter the lower end of the body member or tube 10. It will be readily understood that adjustment of the bottom member 11 either clockwise or counterclockwise, as seen in Fig. 6, will throw apertures 17 and 14 out of alignment thereby cutting down the amount of air admitted to the bottom of the

tube or body member 10 by so much as the said apertures are out of alinement. By this construction a minimum amount of air can be admitted to the tube and this amount increased as desired to maximum or full aperture opening.

The top member 12 is provided with a flange 18 within which is received the upper end of the body member or tube 10. Extending from the upper end of the flange 18 is a conical portion 19 which terminates in a flat portion 20. The flat portion 20 is provided substantially centrally thereof with an aperture 21. In use the conical portion 19 of the top is inserted within the nostril opening and an inhalation effected through the nostril.

By this construction, inhalation through the nostril draws air through the tube or body member 10 across the medicine indicated in Figs. 2 and 8 by the reference numeral 30. The amount of medicine laden air or vapor drawn through the aperture 21 depends upon the relative position of the apertures 17 and 14 which, as above set forth, if in alinement or coincidence, as illustrated in Fig. 6, permits maximum amount of air and, therefore, a maximum amount of vapor or medicine to be inhaled, while if the parts are in adjustment as illustrated in Fig. 5 there is substantially no vapor or medicine laden air flowing into the nostril and when adjustment of the parts is between the two extremes of Figs. 5 and 6 the vapor delivery will be varied accordingly.

In order to prevent inadvertent loss of vapor through the opening 21 when the inhaler is not in use in the nostril, use is made of a closure cap 22 which has a flange portion 23 to encircle the flange 18 of the top member 12. The upper end of the cap flange 23 is integral with a dome like or semi-spherical member 24 which closes the opening 21.

The modification shown in Figs. 8, 9 and 10 utilizes the cylinder or body member 10, the bottom member 11 and the top member 12 each as above described. Instead of the closure cap 22, or in addition thereto, use is made of a closure mechanism arranged within the body member 10 and top member 12. This closure member comprises a pair of plates 25 and 26, respectively, secured in the upper end of the body member or tube 10 and at the upper end of the top member flange 18; the plates 25 and 26 are adapted to slide on one another upon rotation of the top member 12 and are each provided with a similar substantially semi-circular aperture 27 and 28 respectively. As seen in Figs. 9 and 10, the semi-circular apertures 27 and 28 have the same radius from the center of the plates and may be made to more or less overlap depending upon the position of the top member 12. In other words the top member 12 may be rotated either clockwise or counterclockwise to cause the aperture 27 in the plate 26 to be placed over the aperture 28 in the plate 25. It will be understood that this can be a full coincidence thereby permitting the maximum flow through the said apertures or the overlap may be very minute thereby permitting a minimum flow through said apertures.

The construction just described and including the plates 25 and 26 may be employed as a means for regulating the flow through the body member or tube 10 which can be employed to supplement the said regulation as effected by the apertures 17 and 14, above described, or the said apertures 17 and 14 may permit the maximum flow of air into the tube 10 and the apertures 27 and 28 used to regulate the vapor output. In any event, by

positioning the plates 25 and 26 as illustrated in Figs. 8, 9 and 10 the top of the tube 10 is closed to permit no flow therethrough.

This construction could be placed at the lower end of the body portion and utilize the bottom 15 of the bottom member 11 as the rotatable plate and having an arcuate or elongated aperture therein cooperating with a plate secured in the lower end of the body member or tube 10 and likewise having an arcuate or elongated aperture therein.

It will be understood that instead of supplying the bottom closure member 11 with a plurality of small apertures 17 and the lower end of the tube 10 with a plurality of small apertures 14, use may be made in each instance of an elongated aperture which in the closed position would have positions relative to one another as illustrated in Fig. 9 with respect to apertures 27 and 28, while in the open position the said elongated apertures may more or less coincide.

From the foregoing it will be noted that there has been provided an inexpensive container for forming an inhaler and one which embodies means whereby the amount of air to the inhaler and/or the amount of vapor drawn from the tube or body member 10 is regulated.

What is claimed is:

In an inhaler container a cylindrical body member having its lower end open to permit insertion of medicine, a cup like bottom member for closing the open end of the body member and having a flat bottom and an upwardly projecting relatively short flange exteriorly of and receiving the lower end portion of the body member, said bottom member flange and body member end portion within said flange being rotatable relative to one another, each having apertures adapted to be brought into more or less registry upon relative rotation to regulate the amount of air admitted to the body member, said body member enclosing medicine adapted to be picked up by the air, a top member on said body member provided with an aperture through which the medicine laden air passes, said top member having a flange for enclosing the upper end of the body member, an apertured plate carried by the top member flange, and a second apertured plate carried by the body member, said plates being rotatable relative to one another for bringing the apertures into more or less registry to regulate the amount of medicine laden air drawn through the apertured top member.
